UNITED STATES PATENT OFFICE.

SVEN T. NELSON, OF OAK PARK, ILLINOIS, ASSIGNOR TO SULLIVAN MACHINERY COMPANY, OF BOSTON, MASSACHUSETTS, A CORPORATION OF MASSACHUSETTS.

VALVE.

1,299,761.

Specification of Letters Patent.

Patented Apr. 8, 1919.

Application filed October 7, 1914. Serial No. 865,581.

To all whom it may concern:

Be it known that I, SVEN T. NELSON, a citizen of the United States, and a resident of Oak Park, in the county of Cook and State of Illinois, have invented an Improvement in Valves, of which the following description, in connection with the accompanying drawings, is a specification, like characters on the drawings representing like parts.

10 This invention relates to improvements in valves, and is more especially concerned with automatically acting intake and discharge valves for gaseous fluid compressors, and will be best understood by reference to the following description, when taken in connection with the accompanying drawings of a portion of a compressor equipped with intake and discharge valves embodying my invention.

20 In the drawings:

Figure 1 is a central longitudinal section of a portion of a compressor provided with intake and discharge valves embodying my invention;

25 Fig. 2 is a sectional view on line 2—2 of Fig. 1, looking toward the left;

Fig. 3 is a sectional view on line 3—3 of Fig. 1, looking toward the right;

30 Fig. 4 is an elevation of the guard or stop for the intake valve;

Fig. 5 is an elevation of the same viewed from the right-hand side of Fig. 4;

Fig. 6 is an elevation of the intake valve; and

35 Fig. 7 is an elevation of the discharge valve.

Referring to the drawings, and to the embodiment of my invention which I have selected for illustration, I have there shown 40 as an exemplification of my invention a gaseous fluid compressor comprising a cylinder 10, within which a piston 11 works in the customary manner. The cylinder is provided with a cylinder head 12, which for the 45 purpose of convenience of manufacture and assembly of the parts herein comprises a main head 13 and a separate removable supplemental head 14, secured to the cylinder by a plurality of studs 15. The supplemental head is herein chambered and partitioned 50 to provide an intake chamber 16 and a discharge chamber 17, the intake chamber directly communicating with an intake passage 18 through one or more ports 19, and the discharge chamber directly communicating 55

with a discharge passage 20 through one or more ports 21. Preferably, the supplemental cylinder head is provided with cover plates 22 and 23, for the chambers 16 and 17 respectively, whereby the intake and discharge valves may be rendered accessible for purposes of inspection, without the necessity of removing the entire head. The cover plate 22 is herein secured in place by a plurality of screws 24, and the cover plate 23 60 by a series of screws 25.

The intake and discharge valves may be, and herein are, very similar to each other, though they differ in some respects, principally due to the difference in requirements 70 which call for differences in their valve seats and in their mounting. I will describe the intake valve first.

The latter, as herein shown, comprises a valve body 26 (shown in detail in Fig. 6), 75 interposed between a valve seat 27 and a guard or stop 28, the latter being intended to limit the opening movement of the valve. The valve seat 27, as herein shown, is in the form of a plate of generally segmental shape, 80 secured to the main head 13 by a plurality of screws 29 which pass through the margin of the valve and its guard and serve to secure both to the main head.

The valve body herein consists of a relatively thin, flexible and preferably elastic sheet of material, which in practice will be suitably tempered spring steel. This plate is herein provided with a marginal portion 30, suitably perforated to receive the screws 90 29, while within its marginal portion, the plate is provided with slots, herein a plurality of slots 31—31', 32—32', 33—33', 34—34', 35—35' and 36—36', forming 95 tongues 37, 38—38', 39—39', 40—40', 41—41' and 42—42'. Said tongues constitute elastic valves which in their neutral untensioned condition overlie and normally close suitably formed apertures in the valve seat 27. If desired, there may be a plurality of apertures 100 for each tongue, as described in connection with the discharge valve, as will presently appear; but for the purpose of illustrating two desirable forms of valve seats, I have herein shown the valve seat 27 as being provided with a plurality of apertures 43, 44—44', 45—45', 46—46', 47—47', and 48—48', generally corresponding with the tongues of the valve body as to shape and location, though somewhat smaller than the 105 110

tongues so that the marginal portions of the latter normally rest against the valve seat about the margins of the apertures.

The guard or stop 28 (shown in detail 5 in Figs. 4 and 5) may be, and herein is, identical in outline with the valve body, and comprises a marginal portion 49 suitably perforated to receive the screws 29, and a plurality of slots 50—50', 51—51', 52—52', 10 53—53', 54—54', and 55—55', forming tongues 56, 57—57', 58—58', 59—59', 60—60', and 61—61', corresponding to the tongues of the valve body just described. The marginal portion 49 of the guard preferably 15 clamps the marginal portion or base of the tongues securely to the cylinder head as far forward as the point at which, due to the merging of the tongues with the valve marginal portion, the flexibility of the 20 tongues is decreased, that is the junction of the tongues with the marginal portion. This preferred construction results in a projecting valve tongue which has the same flexibility throughout its length independent 25 of the shape of the inner ends of the slots, herein shown as rectangular, although, as is obvious, the inner ends of these slots may assume any desired shape.

The valve guard differs, however, from 30 the valve body, in that it is relatively thick and inflexible, so that its tongues may act as stops for the tongues of the valve body; and moreover, the tongues of the guard or stop are bent or curved out of the plane of 35 the marginal portion of the guard, in order to permit the necessary opening movement of the tongues of the valve body the tongues gradually opening out against or folding up on the curved plates without shock or 40 hammering. For this purpose the curved surfaces of the guards are preferably curved more at the guard ends than at the base of the guards, that is the curvature varies directly as the length of the guard. From 45 an inspection of Fig. 5, it will be observed that the tongues which are nearer the ends of the series have a somewhat greater curvature than those at the central portion thereof, this being for the purpose of permitting 50 a greater amplitude of movement of the shorter tongues to allow for the passage of a somewhat greater volume of air in proportion to their size. Owing to the described form and arrangement of the valve, it is 55 possible to secure a relatively large effective area of the intake. In order to provide for the passage of the gaseous fluid from the intake valve into the cylinder itself, the main head 13 is appropriately apertured, and 60 preferably is provided with a multiplicity of small perforations 62, so that should the valve become broken, the pieces thereof would not become lodged in the end of the cylinder and cause damage. It should here 65 be observed that the main head is provided

with a recess 63, into which the tongues of the guard or stop 28 project.

Turning now to the discharge valve, the latter herein comprises a valve body 64, preferably consisting of a relatively thin, 70 flexible, and preferably elastic sheet of material, which in practice, as in the case of the intake valve, is made of tempered spring steel. This plate is provided with slots 65—65', 66—66', 67—67', 68—68', 69—69', 75 forming a plurality of tongues 70, 71—71', 72—72', 73—73', 74—74', and 75—75', all of which project from a marginal portion 76, suitably perforated to receive a plurality of screws 77. This valve body is herein interposed between a valve seat 78, constituting a part of the main head 13, and a stop or guard 79. The valve body and the guard are secured in place by the screws 77 already referred to, in co-operation with a 80 clamping bar 80.

The valve seat 78 is provided with appropriate apertures, which the tongues of the valve body overlie, and in this instance I have shown a plurality of perforations for 90 each tongue. This construction I prefer to the use of the slots described in connection with the intake valve, for the reason that, where each valve port is made up of a number of small perforations, a better support is provided for the valve tongue, and there is less likelihood of breakage than in the case where each tongue is supported by the valve seat merely at the margin of the tongue. In the form shown, it will be 100 observed that there are several rows of such perforations, the same being herein designated by the numerals 81, 82—82', 83—83', 84—84', 85—85', and 86—86', one series or 105 row for each tongue of the valve body.

Referring now to the stop or guard 79, the latter is herein identical in outline with the valve body itself, though it differs therefrom in being made of a relatively thicker and stiffer plate which will possess the necessary rigidity to limit the opening movement of the valve. This plate is herein provided with a plurality of slots 87—87', 88—88', 89—89', 90—90', and 91—91', forming a plurality of tongues 92, 93—93', 94—94', 95—95', 96—96', and 97—97', corresponding to the tongues of the valve body and respectively overlying them. These tongues, like those of the intake valve, are curved or bowed outwardly from the plane of the valve body to provide the necessary space for the opening movement of the tongues. These tongues, moreover, will have their degrees of curvature to correspond to the degrees of curvature of the intake valve; that is to say, the shorter tongues have a greater curvature in proportion to their length than the relatively longer tongues. This feature I have deemed it unnecessary to illustrate in the case of the discharge valve, because it 130

is well illustrated in the case of the intake valve. In the case of the discharge valve, the use of a series of small perforations for the ports in the valve seat is to be preferred, 5 not only for the reason already mentioned, but because of the fact that in case of breakage of the tongues the pieces would not be so apt to drop into the cylinder chamber and cause damage to the machine. Both of the 10 valves and the parts co-operating therewith are accessible upon the removal of the supplemental head or the cover plates, making it an easy operation to inspect or change any of the valve mechanism.

15 The operation of the valves should be readily understood without any further description, except to say that when the piston travels toward the left (Fig. 1), the discharge valve will naturally remain seated, 20 while the intake valve will be opened by reason of the rarefaction of the gaseous fluid within the cylinder and the relatively higher pressure of gaseous fluid in the intake chamber. On the other hand, when the piston 25 travels toward the right (Fig. 1), the intake valve will naturally be seated by the pressure of the gaseous fluid exerted thereagainst from within the piston chamber, and the compressed fluid will cause the discharge 30 valve to open and permit the fluid to flow from the cylinder chamber to the discharge chamber, and thence to the discharge passage, from whence it will pass to the usual receiver.

35 While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated 40 form or embodiment of the invention may be made, without departing from the principles thereof.

Having thus described my invention, what I claim and desire by Letters Patent to procure is:—

50 1. A valve comprising, in combination, a flat ported seat, a thin, elastic, reed-like metal tongue of greater length than width fixed at one end and free at the other end, adapted to be flexed by fluid pressure and normally resting on said seat without substantial tension, and a stop for said tongue curved only in the direction of the length of 55 said tongue to receive the same, said stop engaging said tongue at its fixed end, and curving gradually away therefrom toward its free end when said tongue is in normal position.

60 2. In a compressor valve, in combination, 65 a flat ported seat, a valve comprising a plu-

rality of thin, elastic, reed-like metallic tongues of greater length than width fixed at one end and free at the other end, adapted to be flexed by fluid pressure and normally resting on said seat without substantial tension, and ported stopping means for said tongues curved only in the direction of the length of said tongues to receive the same, said stopping means engaging said valve at its fixed end and curving gradually away 70 therefrom toward its free end when said valve is in normal position.

3. In a compressor valve, in combination, a flat ported seat, a valve comprising a plurality of thin, elastic, reed-like metallic 80 tongues of greater length than width disposed in spaced relation substantially in the form of a segment, fixed at one end and free at the other end, adapted to be flexed by fluid pressure and normally resting on said seat without substantial tension, and ported stopping means for said tongues curved only in the direction of the length of said tongues 85 to receive the same, said stopping means engaging said valve at its fixed end and curving gradually away therefrom toward its free 90 end when said valve is in normal position.

4. In a compressor valve, in combination, a flat ported seat, a valve comprising a body portion having a plurality of spaced, thin, 95 elastic, reed-like metallic tongues of greater length than width adapted to be flexed by fluid pressure and normally resting on said seat without substantial tension, and stop members curved only in the direction of the length of said tongues and rigidly clamping the same to said seat at a point as far forward as their junction with said body portion and thereafter curving gradually away 100 therefrom when said tongues are in normal 105 position.

5. A valve comprising, in combination, a flat ported seat, a valve member including a plurality of thin, elastic, reed-like metallic tongues of different lengths and all of greater 110 length than width, each fixed at one end and free at its other end, said tongues being adapted to be flexed by fluid pressure and normally resting on said seat without substantial tension, and stopping means for said 115 tongues curved only in the direction of the length of said tongues to receive the same, said stopping means engaging said tongues at their fixed ends and curving gradually away therefrom toward their free ends when 120 said tongues are in normal position, and being provided with ports disposed in staggered relation to the ports in said seat.

6. A valve comprising, in combination, a flat ported seat, an elastic metal body consisting of a plurality of tongues of different 125 lengths connected and fixed at one end and free at their other ends, said tongues adapted to be flexed by fluid pressure and normally resting on said seat without substan- 130

tial tension, and stops for said tongues curved only in the direction of the length of said tongues to receive the same, said stops engaging said tongues at their fixed ends and 5 curving gradually away therefrom toward their free ends when said tongues are in normal position.

7. A valve comprising, in combination, a flat ported seat, an elastic metal body consisting of a plurality of tongues of different lengths connected and fixed at one end and free at their other ends, said tongues adapted to be flexed by fluid pressure and normally resting on said seat without substantial tension, and stops for said tongues curved only in the direction of the length of said tongues to receive the same, said stops engaging said tongues at their fixed ends and curving gradually away therefrom toward their free ends 15 when said tongues are in normal position, the curvature varying directly as the length of the tongues.

8. A valve comprising, in combination, a flat ported seat, a plurality of tongues of different lengths fixed at one end and free at their other ends, adapted to be flexed by fluid pressure and normally resting on said seat without substantial tension, and a stop for said tongues having surfaces curved only 20 in the direction of the length of said tongues to receive the same, said stops engaging said tongues at their fixed ends and curving gradually away therefrom toward their free ends when said tongues are in normal position, 25 the curvature varying directly as the length of the tongues.

9. A valve comprising, in combination, a flat ported seat, a thin, elastic, reed-like metal tongue of greater length than width 30 fixed at one end and free at the other end, adapted to be flexed by fluid pressure and normally resting on said seat without substantial tension, and a stop for said tongue of substantially the width of said tongue 35 having a face to receive the back of said tongue without transverse flexure thereof, said stop engaging said tongue at its fixed end and longitudinally curving gradually away therefrom toward its free end when 40 said tongue is in normal position.

10. A valve comprising, in combination, a flat ported seat, a plurality of thin, reed-like tongues of greater length than width fixed at one end and free at their other ends, 45 adapted to be flexed by fluid pressure and normally resting on said seat without substantial tension, and a stop for said tongues having spaced surfaces to receive the backs of said tongues without transverse flexure thereof, said stop engaging said tongues at 50 their fixed ends and longitudinally curving gradually away therefrom toward their free ends when said tongues are in normal position.

65 11. A valve comprising, in combination, a

flat ported seat, a plurality of tongues held at one end and free at their other ends, adapted to be flexed by fluid pressure and normally resting on said seat without substantial tension, and a stop for said tongues 70 having spaced surfaces to receive the backs of said tongues without transverse flexure thereof and longitudinally curving gradually away therefrom toward their free ends, the curvature varying directly as the length 75 of the tongues.

12. A compressor having a cylinder head space divided into intake and discharge portions and having the area of each portion substantially covered with flat ported valve 80 seats, valves in each of said portions and each comprising a plurality of thin, elastic, reed-like tongues of different lengths to substantially fill the space available in each of said head portions, each of said tongues being of greater length than width, being fixed at one end and free at the other end, adapted to be flexed by fluid pressure, and normally resting on its seat without substantial tension, and stopping means for said tongues 90 curved only in the direction of the length of said tongues to receive the same, said stopping means engaging said tongues at their fixed ends and curving gradually away therefrom toward their free ends when said 95 tongues are in normal position.

13. A compressor having a cylinder head space divided into separate intake and discharge portions, flat valve seats having ports leading from said spaces into said cylinder, 100 valves in said portions comprising a plurality of thin, elastic, reed-like tongues of greater length than width fixed at one end and free at the other, adapted to be flexed by fluid pressure, and normally resting on 105 their seats without substantial tension, the valves in one portion of said head space being on the opposite side of said ports from the valves in the other, and guard members for said tongues curved only in the direction 110 of the length of said tongues to receive the same, said guard members engaging said tongues at their fixed ends and curving gradually away therefrom toward their free ends when said tongues are in normal position. 115

14. A compressor having a cylinder, a main cylinder head and a supplemental head providing between them a space communicating with said cylinder through ported valve seats and subdivided into separate intake and discharge portions by a suitable partition wall, elastic plate valves in each of said spaces arranged to cover the area of said seats, and curved guards for said valves disposed in said portions on opposite 120 sides of said valves.

15. A compressor having a cylinder head closing means subdivided into separate intake and discharge portions and presenting ported valve seats, a series of valves in each 130

of said portions, each of said valves comprising an elastic tongue adapted to be flexed by the pressure of the fluid and normally lying flat and untensioned parallel with said 5 seats, and curved guards for said valves carried by said closing means and disposed on opposite sides of said valves.

16. A compressor having a cylinder, a cylinder head divided into separate intake 10 and discharge portions and having a series of ports leading from each of said portions into the cylinder, a series of valves in each of said portions, each of said valves comprising an elastic tongue adapted to be flexed 15 by the pressure of the fluid and normally lying flat and untensioned parallel with the head, and curved guards for said valves carried by said head and disposed on opposite sides of said valves.

20 17. A compressor having a cylinder head formed with intake and discharge spaces, ports in the intake space formed in a separate plate or body secured to the cylinder head, elastic tongues held at one end and 25 free at the other end normally closing said ports and adapted to be flexed toward said head, ports in the discharge space, said ports being formed in the head, and similar tongues normally closing said ports and 30 adapted to flex away from said head.

18. A compressor having a main cylinder head and a supplemental head providing between them a cylinder head space subdivided into separate intake and discharge portions 35 by a suitable partition wall, ports in the intake space formed in a plate or body adjacent the cylinder head, elastic tongues held at one end and free at the other end normally closing said ports and adapted to be flexed 40 toward said head, ports in the discharge space, said ports being formed in the head, and similar tongues normally closing said ports and adapted to flex away from said head.

45 19. In a compressor, in combination, a cylinder, a cylinder head having a plurality of series of ports therein, a supplemental head divided into intake and discharge spaces communicating with said ports, a 50 ported member disposed in said supplemental head, and elastic valve members one normally disposed over one of said series of ports in said cylinder and the other normally disposed over the ports in said ported member and between said ported member and the 55 remaining ports in said cylinder head.

20. In a compressor, in combination, a cylinder, a cylinder head having a plurality of series of ports therein, a supplemental head divided into intake and discharge spaces communicating with said ports, a 60 ported member disposed in said supplemental head, elastic valve members one normally disposed over one of said series of ports in 65 said cylinder and the other normally dis-

posed over the ports in said ported member and between said ported member and the remaining ports in said cylinder head, and guard members for said valves disposed on opposite sides of the same.

70

21. In a valve for permitting the flow of fluid in one direction but preventing its flow in the opposite direction, the combination of an elastic valve-body adapted to be flexed by the pressure of the fluid and provided 75 with slots forming tongues projecting from a marginal portion and separated by said slots, a valve seat provided with apertures which said tongues overlie and normally close, and a stop or guard provided with openings 80 and imperforate portions to receive the tongues of the valve-body, the latter being interposed between said seat and said stop.

22. In a valve for permitting the flow of fluid in one direction but preventing its 85 flow in the opposite direction, the combination of an elastic valve-body adapted to be flexed by the pressure of the fluid and provided with slots forming tongues projecting from a marginal portion and separated 90 by said slots, a valve seat provided with apertures which said tongues overlie and normally close, and a stop or guard similarly provided with slots forming tongues projecting from a marginal portion and respectively 95 overlying the tongues of the valve-body, the latter being interposed between said seat and said stop.

23. In a valve for permitting the flow of fluid in one direction but preventing its flow 100 in the opposite direction, the combination of an elastic valve-body adapted to be flexed by the pressure of the fluid and provided with slots forming tongues projecting from a marginal portion and separated by said 105 slots, said tongues progressively decreasing in length from one point to another, a valve seat provided with apertures which said tongues overlie and normally close, and a stop or guard provided with openings and 110 imperforate portions to receive the tongues of the valve-body, the latter being interposed between said seat and said stop.

24. In a valve for permitting the flow of fluid in one direction but preventing its flow 115 in the opposite direction, the combination of an elastic valve-body adapted to be flexed by the pressure of the fluid and provided with slots forming tongues projecting from a marginal portion and separated by said 120 slots, said tongues progressively decreasing in length from one point to another, a valve seat provided with apertures which said tongues overlie and normally close, and a stop or guard provided with openings and 125 imperforate portions to receive the tongues of the valve-body, the latter being interposed between said seat and said stop, some of the tongues of said guard being formed to permit a greater amplitude of movement of 130

each valve-body tongue than the relatively longer tongues.

25. In a valve for permitting the flow of fluid in one direction but preventing its flow in the opposite direction, the combination of an elastic valve-body adapted to be flexed by the pressure of the fluid and provided with slots forming tongues projecting from a marginal portion and separated by said slots, a valve seat provided with a plurality of series of perforations, one series for each tongue, which said tongues overlie and normally close, and a stop or guard provided with openings and imperforate portions to receive the tongues of the valve-body, the latter being interposed between said seat and said stop:

26. In a valve for permitting the flow of fluid in one direction but preventing its flow in the opposite direction, the combination of an elastic valve-body of generally segmental form adapted to be flexed by the pressure of the fluid and provided with slots forming tongues projecting from a marginal portion and separated by said slots, a valve seat provided with apertures which said tongues overlie and normally close, and an apertured stop or guard having portions to receive the tongues of the valve-body, the latter being interposed between said seat and said stop.

27. In a valve for permitting the flow of fluid in one direction but preventing its flow in the opposite direction, the combination of an elastic valve-body adapted to be flexed by the pressure of the fluid and provided with slots forming tongues projecting from a marginal portion and separated by said slots, a valve seat provided with apertures which said tongues overlie and normally close, an apertured stop or guard having portions to receive the tongues of the valve-body, the latter being interposed between said seat and said stop, and an apertured mounting for said valve-body and stop, said mounting being recessed to receive the tongues of said stop.

28. In a valve for permitting the flow of fluid in one direction but preventing its flow in the opposite direction, the combination of an elastic valve-body having a marginal portion and provided with slots forming a series of elastic tongues entirely surrounded by said marginal portion and adapted to be flexed by the pressure of the fluid, means for securing said marginal portion, a valve-seat provided with apertures which said tongues overlie and normally close, and means for limiting the opening movement of said valve-body tongues.

29. As a new article of manufacture, a valve-body consisting of a relatively thin elastic plate of generally segmental form having a marginal portion and a plurality

of tongues projecting therefrom toward the curved edge of the plate.

30. As a new article of manufacture, a valve-body consisting of a relatively thin elastic plate of generally segmental form having a marginal portion and provided with a plurality of slots forming a group of tongues entirely surrounded by said marginal portion.

31. In a valve for permitting the flow of fluid in one direction, but preventing its flow in the opposite direction, the combination of a plane elastic valve body adapted to be flexed by the pressure of the fluid and provided with slots forming tongues projecting from a marginal portion and separated by said slots, said tongues progressively decreasing in length from one point to another, and a valve seat provided with apertures which said tongues overlie and normally close.

32. In a valve for permitting the flow of fluid in one direction but preventing its flow in the opposite direction, the combination of an elastic valve body of generally segmental form adapted to be flexed by the pressure of the fluid, and provided with slots forming tongues projecting from a marginal portion and separated by said slots, and a valve seat provided with apertures which said tongues overlie and normally close.

33. In a valve for permitting the flow of fluid in one direction but preventing its flow in the opposite direction, the combination of an elastic valve body having a marginal portion and provided with slots forming a series of elastic tongues entirely surrounded by said marginal portion and adapted to be flexed by the pressure of the fluid, means for securing said marginal portion, and a valve seat provided with apertures which said tongues overlie and normally close.

34. In a compressor, in combination, a cylinder head having a plurality of series of ports therein, a supplemental cylinder head divided into intake and discharge spaces, a ported member disposed in said supplemental head having its ports opposite certain of the ports in said cylinder head, elastic valve members normally disposed over certain of the ports in said cylinder head and the ports in said ported member, said last mentioned valve members being disposed between said ported member and the remaining ports in said cylinder head, guard members disposed on opposite sides of said valve members, and means for clamping said valves and guard members in position.

35. In a compressor, in combination, a cylinder head having a plurality of series of ports therein, a supplemental cylinder head divided into intake and discharge spaces, a ported member disposed in said supplemental head having its ports opposite

- certain of the ports in said cylinder head, elastic valve members normally disposed over certain of the ports in said cylinder head and the ports in said ported member, 5 said last mentioned valve members being disposed between said ported member and the remaining ports in said cylinder head, guard members disposed on opposite sides of said valve members, means for clamping 10 said valves and guard members in position, and means whereby access may be had to said clamping means from the exterior of said supplemental head.
36. In a compressor, in combination, a 15 cylinder head having a plurality of series of ports therein, a supplemental cylinder head divided into intake and discharge spaces, a ported member disposed in said supplemental head having its ports opposite certain of the ports in said cylinder head, elastic valve members normally disposed over 20 certain of the ports in said cylinder head and the ports in said cylinder member, said last mentioned valve members being disposed between said ported member and the remaining ports in said cylinder head, guard 25 members disposed on opposite sides of said valve members, means for clamping said valves and guard members in position, means whereby access may be had to said clamping 30 means from the exterior of said supplemental head, and means whereby said supplemental head may be bodily removed from said cylinder head.
37. A valve comprising, in combination, a 35 flat ported seat, a thin, elastic, reed like, metal tongue of greater length than width fixed at one end to a marginal valve portion, the latter being held securely to said seat as far forward as its junction with said tongue, said tongue having its other end 40 free and adapted to be flexed by fluid pressure, and normally resting on said seat without substantial tension, and a stop for said tongue curved only in the direction of the 45 length of said tongue to receive the same, said stop engaging said tongue at its fixed end and curving gradually away therefrom toward its free end when said tongue is in normal position.
- In testimony whereof, I have signed my name to this specification, in the presence of two subscribing witnesses.

SVEN T. NELSON.
